UNITED STATES PATENT OFFICE.

WILLIAM BUTTLER, OF FOSTORIA, OHIO, ASSIGNOR TO THE BUTTLER ART GLASS COMPANY, OF SAME PLACE.

DESIGN FOR WINDOW-GLASS.

SPECIFICATION forming part of Design No. 19,054, dated April 23, 1889.

Application filed March 30, 1889. Serial No. 305,458. Term of patent 7 years.

To all whom it may concern:

Be it known that I, WILLIAM BUTTLER, of Fostoria, in the county of Seneca and State of Ohio, have invented a new and original Design for Window-Glass, of which the following is a full, clear, and exact description.

My invention relates to a design for window-glass or cathedral-glass; and it consists in the design hereinafter described, and particularly stated in the following claim.

Figure 1 of the accompanying drawings shows in plan view a sheet of glass provided with my design. Fig. 2 is a vertical cross-section on the line II II of Fig. 1.

As shown in the drawings, the glass is provided with a surface pattern consisting of a number of irregularly disposed and shaped

intersecting lines or stripes *in intaglio*, having irregular non-connecting lateral branches, as shown. Such pattern is very neat and beautiful in appearance.

I claim—

The design for window-glass, consisting in a glass sheet provided with a surface pattern composed of a number of irregularly disposed and shaped intersecting lines or stripes *in intaglio*, having irregular lateral branches, substantially as herein shown and described.

In testimony whereof I have hereunto set my hand this 25th day of March, A. D. 1889.

WILLIAM BUTTLER.
